CLAIM

The ornamental design for a snow board pole, as shown and described.

DESCRIPTION

FIG. 1 is a rear perspective view of a snow board pole, taken to a reduced scale, showing my new design;

FIG. 2 is a fragmentary front perspective view of the upper portion of the snow board pole;

FIG. 3 is a top plan view, thereof;

FIG. 4 is a bottom plan view, thereof;

FIG. 5 is a rear elevational view, thereof;

FIG. 6 is a side elevation of the snow board pole, the opposite side elevation is a mirror image thereof except for the continuous threading below the handle; and,

FIG. 7 is a front elevational view, thereof.

The broken line representation of the pole basket is included solely for illustrative purposes, forming no part of the claimed design.

The lower portion of the snow board pole has been omitted in FIG. 2 for ease of illustration. Portions of the shaft of the snow board pole are shown broken away in FIGS. 5, 6 and 7 for ease of illustration. The views in the drawings are shown on different scales.
